UNITED STATES PATENT OFFICE.

BYERS W. KADEL, OF BALTIMORE, MARYLAND, ASSIGNOR, BY MESNE ASSIGNMENTS,
TO THE SYMINGTON COMPANY, A CORPORATION OF MARYLAND.

BACKSTOP.

Application filed November 30, 1923. Serial No. 677,731.

To all whom it may concern:

Be it known that I, BYERS W. KADEL, a citizen of the United States, residing at Baltimore, in the State of Maryland, have 5 invented certain new and useful Improvements in Backstops; and I do hereby declare the following to be a full, clear, and exact description of the invention, such as will enable others skilled in the art to which 10 it appertains to make and use the same.

The invention relates to draft rigging for railway cars and more particularly to a stop member adapted to cooperate with a movable member of the draft rigging and serve 15 as a tie means to rigidly connect the draft or center sills and prevent their spreading.

One of the principal objects of the invention, generally stated, is to provide a backstop casting of great strength value but 20 of comparatively light weight, which can be effectively connected to the car sills with a minimum expenditure of labor.

Particularly stated, the principal features 25 of the invention is to provide a backstop with spaced side walls united at their forward ends by a transverse or end wall forming the buffering web or abutment with which the yoke of the drafting rigging contacts, 30 said walls being united by a bottom or floor web and transversely disposed upwardly inclined webs, said last named webs acting to reinforce the buffering web and having disposed above and below the same a plurality of rivet openings, the forward lowermost 35 openings being readily accessible by reason of the relative spacing of the front edge of the bottom web and the lowermost edge of the buffering web, the vertically disposed longitudinally extending web reinforcing 40 the buffering web also being shaped to permit free access to the lowermost front rivet openings without impairing their strength value.

Other features of the invention residing in 45 the particular details of construction and characteristic relation of structural parts, will hereinafter appear.

In the drawings illustrating the invention, the scope whereof is pointed out in the 50 claims:

Figure 1 is a plan view of a backstop embodying the invention.

Figure 2 is an end elevation viewed from the forward or front end of the casting.

Figure 3 is a vertical longitudinal sec- 55 tional view on the line 3—3 of Figure 1.

Figure 4 is a vertical transverse sectional view on the line 4—4 of Figure 3.

Referring to the drawings in which similar reference characters designate corresponding parts in the several views, the casting involves spaced side walls 1 and 2 united at their forward or front end by the transverse wall 3 and at their rear end by the 60 transverse wall 4.

A bottom wall or floor portion 5 unites the lower edge of the side walls intermediate the front and rear walls, and a center thimble 6 extends therefrom for receiving the king bolt. An intermediate vertically dis- 70 posed transversely extending web 7 unites the spaced side walls, said web intersecting the center thimble, as shown.

Each side wall of the casting is provided 75 with a series of rows of longitudinally arranged openings adapted to receive the rivets which are used to connect the casting to the car sills, the casting being designed to permit easy access to the rivet openings and particularly the lower ones 80 at the front of the side walls.

The side walls throughout their length are united laterally of the casting by upwardly inclined longitudinal webs 8 which converge toward the center of the casting, 85 said webs uniting the side walls with the buffering web and transverse web 7 and providing a very strong reinforcement for said buffering web. Each of the inclined webs 8 is intersected by a vertically disposed web or 90 rib 9 arranged relatively close to the center of the casting and having a portion extending above and below the same, said webs 9 acting to reinforce the buffering wall and having their lower portions spaced above 95 the lower front openings in the side walls to readily permit the insertion of the rivets and the connecting of the casting to the car sills.

The casting is provided with a vertically 100 disposed longitudinally extending web 10 located centrally of the casting, said web uniting the floor portion, buffering wall and upwardly converging web 8. The vertical web is also united with the center thimble 105 and acts to reinforce the buffering wall, said web at its lower front end being cut away as at 10^a to provide ample space for effec-

tively riveting the lower front part of the casting to the draft or center sills. The upper part of the web 10 projects above the upwardly converging webs 8 at their junction and reinforces the buffing web forwardly of the center thimble.

The vertical web is continued rearwardly of the center thimble below the upwardly converging webs 8 and connects the rear wall 10 with the bottom wall or floor portion 5. Portions of the side and adjacent bottom walls are inwardly offset, as shown, to provide space for the inside reinforcing angles shown in dotted lines in Figure 2. Triangular shaped openings 11 may be provided in the upwardly converging web 8, said openings being preferably located between the transverse web 7 and rear wall 4 of the casting, as best shown in Figure 1.

20 A casting constructed in accordance with the present invention permits of the forward edge of the bottom wall being located well back from the lower edge of the buffing wall without sacrificing the strength value of 25 the casting or increasing the weight, it being observed that the shape of the reinforcing webs and their section moduli are relatively large for the amount of metal used, said webs being advantageously located throughout the casting to uniformly distribute the loads to the major portions of the casting without deformation and at the same time permit access to all rivet openings in a very convenient manner, thereby assuring the 35 most effective connecting of the casting to the car sills.

I claim:

1. A backstop casting for railway draft rigging involving spaced side walls having a plurality of openings therein, said walls being united at their front ends by a transverse wall forming a buffing web, a floor portion uniting the side walls, the front edge of said floor portion being spaced rearwardly from the buffing web and disposed below the lower edge thereof to provide a relatively large space for access to some of said openings in the forward lower portion of the side walls, and a plurality of longitudinally disposed substantially parallel reinforcing flanges for said buffing web, said flanges being spaced from the side walls and floor portion.

2. A backstop casting for railway draft rigging comprising spaced side walls having a plurality of rivet openings therein, a transverse wall forming a buffing web uniting the side walls at their front ends, a floor portion connecting the side walls in the rear of the front ends thereof, said floor portion being located below the bottom edge of the buffing wall to permit convenient access to the rivet openings, a vertically arranged longitudinally disposed web uniting the buffing web and floor portion centrally of the casting,

longitudinally extending upwardly inclined webs uniting the vertically arranged web to an adjacent side wall, and a vertically arranged longitudinally extending web located upon each side of the centrally arranged vertical web and intersecting one of said upwardly inclined webs, said last named webs having their lowermost edges terminating above the rivet openings located in the lower forward portions of the side walls.

3. A backstop for railway draft rigging involving spaced side walls having rivet openings at their lower forward ends, a bottom wall uniting said side walls and having its forward edge spaced from the front ends of the side walls, a transverse buffing wall uniting the front ends of the side walls and having its lower edge arranged in spaced relation from the forward edge of the bottom wall, a centrally located vertical web longitudinally uniting the buffing and bottom walls, and a reinforcing web located upon each side of said centrally located web, each of said webs having its bottom portion terminating short of the said rivet openings.

4. A backstop for railway draft rigging involving spaced side walls having rivet openings at their lower forward ends, a bottom wall uniting said side walls and having its forward edge spaced from the front ends of the side walls, a transverse buffing wall uniting the front ends of the side walls and having its lower edge arranged in spaced relation from the forward edge of the bottom wall, vertically and laterally arranged intersecting webs reinforcing said buffing wall and uniting the same with the bottom and side walls, said intersecting webs having their lower portions disposed to permit convenient access to the aforesaid rivet openings.

5. A backstop casting for railway draft rigging involving spaced side walls each having a plurality of rows of longitudinally disposed rivet openings, a transverse wall uniting the forward ends of the side walls and forming a buffing web, a bottom wall uniting the lower edges of the side walls, said bottom wall having its front edge arranged in spaced relation from the lowermost edge of said transverse wall, transversely arranged upwardly converging webs uniting the side walls and transverse buffing web, said converging webs extending between certain of the longitudinal rows of rivets, and vertically disposed webs intersecting said upwardly converging webs for reinforcing the buffing wall, said last named webs having their lower edges spaced above and inwardly from the rivet openings lying beneath the upwardly converging wall for permitting convenient access to said openings.

6. A combined tie and backstop casting

for railway draft rigging involving spaced side walls each having a plurality of rows of rivet openings, a transverse wall uniting the side walls at their forward ends and 5 forming a buffering wall, a rear wall uniting said side walls, a bottom wall uniting the side walls intermediate their front and rear ends, a center thimble projecting from said bottom wall, a transverse web uniting the 10 bottom wall, side walls and center thimble, upwardly converging webs uniting the front,

rear and side walls, said webs intersecting the center thimble, and a plurality of vertically arranged longitudinally extending reinforcing webs having portions projecting above and below the upwardly converging webs, said reinforcing webs having their lower edge portions spaced above and inwardly of the lowermost row of rivets in said side walls. 15

In testimony whereof I affix my signature.
